UNITED STATES PATENT OFFICE.

JOHN JACKSON SMITH, OF McDONOUGH, GEORGIA.

GIN-SAW SHARPENING AND GUMMING DEVICE.

1,304,614.

Specification of Letters Patent. Patented May 27, 1919.

Application filed August 12, 1918. Serial No. 249,479.

To all whom it may concern:

Be it known that I, JOHN JACKSON SMITH, a citizen of the United States, and a resident of McDonough, in the county of Henry and 5 State of Georgia, have invented certain new and useful Improvements in Gin-Saw Sharpening and Gumming Devices, of which the following is a specification.

My invention is an improvement in gin saw sharpening and gumming devices, and has for its object to provide mechanism of 10 the character specified for grinding gin saws, wherein a grinding wheel is provided for grinding the throats of the saws, and reciprocating files for finishing the edges of 15 the throats, and wherein other mechanism is provided for advancing the teeth of the saws, the advancing mechanism operating in alternation with the grinding mechanism.

20 In the drawings:

Figure 1 is a top plan view of the improved gin saw sharpening and gumming device;

Fig. 2 is a side view;

25 Fig. 3 is an enlarged sectional detail;

Figs. 4 and 6 are sections on the lines 4—4 and 6—6, respectively, of Fig. 1;

Fig. 5 is a section on the line 5—5 of Fig. 2.

30 Fig. 7 is a section on the line 7—7 of Fig. 3;

Fig. 8 is a plan view of the pawl plate.

The present embodiment of the invention is shown in connection with a series of gin 35 saws 1 arranged upon the mandrel 2 in the usual manner, and the improvement comprises a staff or standard 3 having a suitable base 4 which may rest upon the floor of the gin house, the base being so arranged that the staff or standard will be held in inclined 40 position, inclining toward the saws.

A frame 5 is mounted on the staff or standard, and is adjustable vertically thereof, the frame having at one end a bearing

45 sleeve 6 which is slidable on the standard and which is held in adjusted position by means of a set screw or the like. At the opposite end from the standard the side members converge, as shown, and they are connected to opposite sides of the body of a yoke 7, the arms of the yoke being adapted to engage over the spacing collars 9 between the sides. Thus the frame is supported between the mandrel and the standard 3.

50 A clamping member, consisting of an upper section 10 and a lower section 11, is con-

nected with the body of the yoke at one side thereof, the upper section 10 being riveted to the body of the yoke while the lower section 11 is adjustably connected with the 60 upper section, by means of laterally extending straps 12 and 12^a which are riveted to the upper section, the former being riveted to the lower section and the latter to the upper section, and each strap has a slot 65 through which passes a set screw, to adjustably connect the sections together. The sections 10 and 11 are bent outwardly from each other, as shown, to engage above and below a spacing collar 9. The stop member 70 7 engages on one face of the saw being sharpened while the clamping member engages on the other face, and it will be evident that by loosening the said screws the lower section 11 of the clamping member 75 may drop down to permit easy disengagement of the frame from the mandrel.

A gumming wheel 13 is provided for gumming the throat between the teeth, and the said wheel is secured to one end of a shaft 80 15. This shaft, as shown more particularly in Fig. 4, is sectional, consisting of a section 15 to which the wheel is secured and a section 15^a which has secured at the end remote from the gumming wheel a bevel gear 16 85 meshing with a gear 17 on a drive shaft 18 journaled in brackets 19 on the frame 5. The sections 15 and 15^a at their adjacent ends are received in a tubular casing or sleeve 20, the sections engaging opposite 90 ends of the casing, and the section 15^a is secured to the casing by means of a cap 21 which engages over the end of the casing and is secured to both shaft and casing by means of a set screw 22. The section 15^a has a 95 transverse pin 23 which engages oppositely arranged longitudinally extending slots 24 in the casing, and it will be evident that by loosening the set screw the section 15^a may be adjusted longitudinally of the tubular 100 casing.

A coil spring 25 encircles the tubular casing, being connected at one end to a collar 26 adjustably held on the casing by a set screw 27 and at the other end to a pin 28 connected 105 with the section 15 and extending through one of the slots 24. This spring normally acts to draw the casing 20 toward the shaft 18. The shaft 18 is provided at each end with a disk or fly wheel 29 and each of these 110 disks or fly wheels has a wrist pin eccentric to the shaft 18. The wrist pins are for oper-

ating longitudinally moving files to be presently described, and the shaft has also a gear wheel 30 which meshes with a wheel 31 on a driving shaft 32 journaled in bearing standards 33 on the frame, the said shaft having at one end a crank 34 for convenience in rotating the same.

Each of the files 35 is held in a socket in one end of a rod 36, and each rod is mounted to move in bearing sleeves 37 supported by the frame. The files are held in the sockets by means of set screws as shown, and each rod 36 has a laterally extending pin 37^a intermediate its ends, which engages a bearing sleeve on one end of a link 38. The other end of each link 38 is pivoted to a clip 39 on the wrist pin of the adjacent disk 29. It will be obvious that when the shaft 19 is rotated the links 38 will reciprocate the rods 36, and since these rods converge toward the saws, in such manner that the files 35 cross at the periphery of the saws, that is, just inside the points of the teeth, the opposite faces of the saw will be cut by the files at the throats of the teeth to smooth the same after the grinding by the wheel 13.

Mechanism is provided for advancing the saw being operated upon the distance of one tooth, and this mechanism also controls the lifting and lowering of the grinding wheel to bring it into and out of operative position. The end of the shaft section 15^a adjacent to the shaft 19 is supported by a bearing bracket 40 which is journaled on the shaft 15 to swing with respect thereto. An elbow lever, consisting of an arm 41 and an arm 42, is pivotally connected to the frame near the connection with the body of the yoke 7, as indicated at 43, and the arm 41 which normally extends vertically has an opening through which is passed one end of a rod 44.

This rod is held in adjusted position with respect to the arm 41 by means of a set screw 45, and the other end of the rod has a foot to which is connected pawl mechanism for engaging the teeth of the saw to move the same. This foot 45, as shown in Fig. 6, extends at an angle of approximately forty-five degrees with respect to the body of the rod, and a forked reinforcing plate 46 is secured to the foot by means of screws 47. The arms of the forked plate 46 engage on opposite sides of the saw, and these arms are of such length that their free ends are never beyond the periphery of the saw.

The pawl plate 48 is of relatively thin material and is arranged between the foot and the forked plate, and the openings 48^a for receiving the screws 47 in the said pawl plate are slots extending transversely of the plate so that when that portion of the pawl plate engaging the teeth of the saw becomes worn the plate may be shifted laterally to bring a new surface into engaging position.

The rod 44 is normally drawn downward toward the teeth of the saw by means of a coil spring 49 arranged between the rod and the body of the yoke 7, and it is moved upward by the engagement of a roller 50 extending laterally from the rod with a cam plate 51 secured to one of the arms of the yoke 7. This plate extends upwardly at an angle, as shown, and it will be evident that when the rod is moved longitudinally toward the saw the roller will engage this inclined place and will roll up the same, lifting the pawl, and when the rod is moved in the opposite direction the roller will roll down the inclined plate, permitting the pawl to engage the teeth of the saw. The connection between the arm 41 of the elbow lever and rod 44 is a swinging connection. A bearing block 52 is pivotally connected to the upper end of the arm, as indicated at 53, and the rod passes through this bearing. The set screw 45 is threaded through the bearing into engagement with the rod, and the bearing rocks freely with respect to the arm on a transverse axis 56.

The section 15 of the shaft 15—15^a passes through a bearing sleeve 54 which is mounted to slide vertically in a slot in a bracket arm 55 extending upwardly from the yoke body 7. This bearing sleeve has a portion 54^a which extends through the slot, and a rod 57 which is pivoted at its lower end to the arm 42 of the elbow lever 41—42 passes through this portion 54^a, being slidably connected therewith.

A coil spring 58 encircles the rod between a wing nut 59 threaded on to the top of the rod and the portion 54^a of the sliding bearing. A stop collar 60 is adjustably held on the rod below this portion 54^a by means of a set screw as shown, and it will be obvious that when the lever 41—42 is rocked the rod 57 may move downwardly with respect to the bearing 54 within limits prescribed by the tension of the spring 58, and the tension may be regulated by the wing nut 59. An eccentric rod 61 connects the arm 41 of the elbow lever with a cam 62 on the shaft 32 before mentioned. This eccentric rod 61 has that end adjacent to the cam bent into a cam strap which encircles the cam as shown, and when the shaft 32 is rotated the elbow lever 41—42 will be rocked, to advance the saw and to raise and lower the shaft 15—15^a. Mechanism is provided for lifting the shaft 15—15^a out of engaging position when desired. The said mechanism comprises a lever 63 which is pivoted at 64 to the bracket 55, and this lever has a cam portion or foot 65 which will engage the bearing 54 to lift the same when the lever is swung in the proper direction.

Referring to Fig. 5, it will be seen that the roller 50 is mounted on a journal pin 66 which has a bearing 67 mounted to slide on

the rod 44, and the bearing is held in adjusted position by a set screw 68. By releasing the set screw the roller may be adjusted toward and from the cam plate 51, to cause the pawl plate 48 to be lifted at the proper time.

In operation, the device is engaged with the saws as shown in Figs. 1 and 2, the arms of the stop yoke 7 engaging the spacing collars between the saws at one side of the saw to be ground, the clamp 10—11 engaging at the other side of the saw. When the parts are properly adjusted, the adjustment of the pawl plate of course depending upon the size 15 of the saw teeth, a rotation of the shaft 32 will rock the elbow lever 41—42, to grind between the teeth of the saw, and to advance the saw a distance of one tooth between each grinding operation, the engagement of the 20 grinding wheel and the pawl plate with the teeth being in alternation. As the teeth are ground, they will come to the files 35, which will smooth down the saw at the throats of the teeth. When a saw has been ground 25 the device may be moved to the next saw. It will be noticed that the base plate 4 for the standard 3 has a block 69 secured to the under face thereof, which has its under face inclined to hold the standard at the proper 30 inclination. The stroke of the pawl plate may be nicely adjusted, so that it will never move the saw a distance greater or less than one tooth, by means of the roller 50. By arranging this roller at the proper point it 35 will lift the pawl plate out of engagement with the teeth and lower it into engagement with the teeth at exactly the right points to move the saw the proper distance. The yielding mounting of the sections of the 40 grinding shaft with respect to each other permits some longitudinal movement of the grinding wheel to compensate for irregular teeth in the saws.

It should be noted that just before the 45 feed pawl reaches the saw tooth throat on the return stroke, the roller 50 clears the cam plate or finger 51, and should there be a gap or low place in the gin saw the feed pawl will reach into the low place or gap 50 and rotate the saw cylinder. The spring 49 causes the feed pawl to positively engage the saw tooth throat one tooth at a time. It is very necessary that the feed pawl blade or plate should be of thin steel, in order that it 55 will not wedge or jam in the saw tooth throat and cause the gin saw tooth to be bent or wedged out of its proper or original shape. Because of the thinness of the feed pawl it is backed by the forked plate 46. It 60 will be noticed that the eccentric 62 has more throw or travel than is necessary to engage a tooth at a time, and that as the feed pawl reaches the throat of the tooth, to bring the next tooth to position to be operated upon, the eccentric at that point is just

past the center, and hence the travel of the feed pawl is slowed, avoiding a too sudden movement of the saw cylinder. The moving of the cylinder is a quick and steady movement and there is always a positive stop 70 during the operation of the files and grinding wheel. The feed pawl operating, as it does, at the top of the saw, the entire machine is pressed snugly against the spacing blocks or collars of the cylinder, being always held thus in close contact with the cylinder.

I claim:

1. A device of the character specified comprising a suitable supporting frame 80 having means for engaging the spacing collars between the saws of a gin, a shaft journaled transversely of the frame, a shaft journaled longitudinally of the frame and extending perpendicular to the axis of the saw 85 when the frame is in place, a gumming wheel at the end of the shaft adjacent to the saws for gumming the same, means for advancing the saws tooth by tooth to the action of the gumming wheel, files for dressing the 90 opposite faces of the saw as the teeth are gummed, means controlled by the rotation of the first named shaft for reciprocating the files and for rotating the gumming wheel, means controlled by the rotation of the said 95 shaft for alternately lifting that end of the shaft provided with the gumming wheel and for advancing the saw, said means for advancing the saw comprising a reciprocating pawl having a stroke of a length to advance 100 the saw a greater distance than a single tooth, and means for preventing engagement of the pawl with the teeth beyond predetermined points in its reciprocating movement, said means being adjustable for saws with various size teeth. 105

2. A device of the character specified comprising a suitable supporting frame having means for engaging the spacing collars between the saws of a gin, a shaft journaled transversely of the frame, a shaft journaled longitudinally of the frame and extending perpendicular to the axis of the saw when the frame is in place, a gumming wheel at 110 the end of the shaft adjacent to the saws for gumming the same, means for advancing the saws tooth by tooth to the action of the gumming wheel, files for dressing the opposite faces of the saw as the teeth are 115 gummed, means controlled by the rotation of the first named shaft for reciprocating the files and for rotating the gumming wheel, means controlled by the rotation of the said shaft for alternately lifting that end of the shaft provided with the gumming wheel and 120 for advancing the saw, said means for advancing the saw comprising a reciprocating pawl having a stroke of a length to advance the saw a greater distance than a single tooth, and means for preventing engagement 125 130

of the pawl with the teeth beyond predetermined points in its reciprocating movement.

3. A device of the character specified comprising a suitable support, a shaft journaled longitudinally of the support and having a gumming wheel for engaging the saws, means for rotating the shaft, means controlled by the rotating means for lifting that end of the shaft adjacent to the gumming wheel at predetermined intervals, said gumming shaft consisting of sections movable longitudinally with respect to each other and normally spring held in predetermined relation with respect to each other.
- 10 4. In a device of the character specified, a supporting frame, a gumming shaft mounted to rotate thereon and provided with a gumming wheel, means at the opposite end of the shaft from the gumming wheel for rotating the same, a pawl for engaging the teeth of the saw to advance the teeth in succession to the gumming wheel, means controlled by the rotating means for the gumming shaft for operating the pawl and for lifting the gumming wheel in alternation, said pawl comprising a relatively thin plate for engaging the teeth, a reinforcing plate for the first named plate, said engaging plate being movable laterally with respect to the reinforcing plate to bring different portions of the edge of the engaging plate into engaging position, said reinforcing plate being forked at the end adjacent to the saw and the arms of the fork engaging opposite faces of the saw.
- 15 5. A pawl for advancing saws to be gummed, said pawl comprising a foot, a relatively thin engaging plate for the teeth, a reinforcing plate for the thin plate, said thin plate being arranged between the reinforcing plate and the foot, and being adjustable laterally with respect to the reinforcing plate and the foot for the purpose specified, said reinforcing plate being forked at the end adjacent the saw and the arms of the fork adapted to engage opposite faces of the saw.
- 20 6. A pawl for advancing saws to be gummed, said pawl comprising a foot, a

relatively thin engaging plate for the teeth, 50 and a reinforcing plate for the thin plate, said thin plate being arranged between the reinforcing plate and the foot, and being adjustable laterally with respect to the reinforcing plate and the foot for the purpose 55 specified.

7. A pawl for advancing saws to be gummed, said pawl comprising a foot, a relatively thin engaging plate for the teeth, and a reinforcing plate for the thin plate, 60 said thin plate being arranged between the reinforcing plate and the foot.

8. A pawl for advancing saws to be gummed, said pawl comprising a foot, a relatively thin engaging plate for the teeth, 65 and a reinforcing plate for the thin plate, said thin plate being arranged between the reinforcing plate and the foot, the reinforcing plate being forked at the end adjacent to the saw and the arms adapted to engage 70 on opposite sides of the saw.

9. In a device of the character specified, a suitable support, a gumming shaft journaled on the support, means at one end of the shaft for rotating the same, a gumming 75 wheel at the other end, means controlled by the rotating means of the shaft for lifting the gumming wheel at predetermined intervals, a spring normally pressing the gumming wheel toward the teeth of the saw, 80 and manually controlled means for holding the wheel out of engagement with the teeth.

10. In a device of the character specified, a suitable support, gumming means for the saw, a pawl for advancing the teeth in succession to the gumming means, means for moving the pawl a greater distance than is necessary to advance the saw the distance of a tooth, and means for holding the pawl out 85 of engagement with the teeth at either end of its movement, except during a predetermined extent of its travel, and adjustable to vary the time during which the pawl will be in engagement with the teeth.
